CLOCK OR THE LIKE CASE

Elof L. Carlson, Bristol, Conn., assignor to The
E. Ingraham Company, Bristol, Conn., a cor-
poration

Application March 23, 1932. Serial No. 600,661

6 Claims. (Cl. 58—53)

This invention relates to means for assembling a plurality of interrelated elements in compact, relatively-fixed relation to produce, in effect, a unitary arrangement thereof; and it has to do particularly with metal clock-cases, especially the bezels used therewith, and means whereby the bezels and their associated crystals, dials and/or dial-plates and movement-mounting plates are assembled in substantially-unitary ar-
10 rangement with the bezels.

The object of the invention is, primarily, to provide a means, preferably integral with the bezel, whereby the crystal and other associated parts mentioned may be assembled in and held 15 in fixed relation to the bezel, thereby making necessary very few parts to complete the assembly, and thus providing for ready and easy assembly of the parts and the low manufacturing cost incident thereto.

20 Having the foregoing in mind, the invention contemplates the combination in an assembly of the character mentioned, of a bezel-element including a rim and a flange, the flange offstanding from the rim substantially normal thereto and 25 provided with a plurality of incisions forming lugs, these lugs being capable of being bent substantially radially inward in contact with one of the members associated with the crystal to hold all of the members in fixed relation to the rim 30 of the bezel and to each other, the faces or edges of the lugs in contact with the member upon which they bear being preferably inclined in such manner that when they are progressively bent radially inwardly they will exert upon the 35 crystal and its associated members a progressively increasing pressure, all as will be herein- after more fully explained and finally claimed.

In the accompanying drawing:

Fig. 1 is a fragmentary central vertical sec-
40 tional elevation illustrating a clock-case em-
bodying the features of the invention;

Fig. 2 is an enlarged fragmentary side view of
45 the clock-case, with a part of the clock-move-
ment-enclosing member of the case broken
away;

Fig. 3 is an enlarged fragmentary sectional
50 elevation similar to the lower portion of Fig. 1,
and illustrating in detail the arrangement of the
parts forming the feature of the invention; and

Fig. 4 is a rear perspective view of the bezel
and the parts assembled therewith.

As shown, particularly in Fig. 1, the clock-case
of the invention includes the usual clock-move-
55 ment-enclosing case element, or case proper,
having a back 1 and a cylindrical or other

shaped body 2. Associated with this member is the bezel-element comprising, essentially, a rim 3 having, preferably formed integral with it, an offstanding flange 4 arranged substantially normal to the rim 3 and inset sufficiently from the 60 edge thereof to provide a shoulder 5 against which the edge of the body 2 may abut when the flange 4 of the bezel-element is telescoped into it.

Mounted within the flange 4 of the bezel, and 65 arranged to bear against the rim 3 thereof, are the usual crystal 6, dial 7 and dial-plate 8 and a mounting-plate 9 appropriately formed to support the front and back movement-plates 10 and 11, respectively, which carry the usual clock- 70 movement, not shown. In the embodiment illus-
trated in the drawing, the dial 7 and dial-plate 8 are shown as two separate elements, the dial 7 being represented as a paper or other appro-
priate disk bearing the dial indicia, and pref- 75 arably affixed, as by pasting or other appropriate means, to the dial-plate 8, although it need not, necessarily, be so affixed.

The flange 4 of the bezel-element is provided at appropriate intervals around its periphery 80 with suitably-formed incisions by which are pro-
duced a suitable plurality of lugs 12, herein shown as three in number, which are bendable substantially radially inward into engagement with the exposed rear surface of the mounting- 85 plate 9 to hold the crystal, dial, dial-plate and mounting-plate in fixed relation relatively to each other and to the bezel, so that all of these parts, along with the clock-mechanism, may be removed, with the bezel, from the clock-case 90 proper as a unit.

As shown particularly in Figs. 1, 2 and 3, the bendable lugs 12 are so cut out that their edges 13, which will after bending bear against the mounting-plate 9, are of inclined or cam- 95 like contour. By virtue of this contour the lugs 12 will, as they are bent radially inward relatively to the mounting-plate 9, exert a pro-
gressive camming action upon this plate and therethrough upon the dial-plate 8, dial 7 and 100 crystal 6 to progressively force these parts, with gradually increasing pressure, against the rim 3 of the bezel, thus, in a sense, securely wedging these parts against the rim 3 and within the bezel, and holding them thereagainst and therein 105 firmly and securely to thus prevent undesired movement of them relatively to the bezel and to each other.

Obviously, due to the formation and arrange-
110 ment of the lugs 12, the parts held in the bezel

thereby may be removed simply by bending the lugs outwardly substantially to their original form.

In addition to the relative ease and facility with which the assembly and disassembly of the parts mentioned may be accomplished by the construction, arrangement and method of forming or bending the lugs into position relatively to the parts held by them, it will be noted that they present no projections which protrude beyond the outer periphery of the flange 4, and thus present no obstructions against which the body 2 of the case proper will strike when the case and bezel-element are telescoped together. It will thus be seen that, by this invention, there is provided a very simple, cheap and efficient means for assembling the related parts mentioned, the structure and operation of the lugs, particularly, presenting advantages over anything of a similar nature now known.

Various changes and modifications are considered to be within the spirit of the invention and the scope of the following claims.

I claim:

- 25 1. In a clock-case, a bezel-element adapted to receive in assembled relation a crystal, a dial and a movement-mounting plate, said bezel-element having a rim for engagement with said crystal and a flange offstanding substantially normal therefrom, said flange cut to provide a plurality of lugs bendable into engagement with said mounting-plate to hold said mounting-plate, dial and crystal in relatively fixed relation to said rim.
- 35 2. In a clock-case, a bezel-element adapted to receive in assembled relation a crystal, a dial and a movement-mounting plate, said bezel-element having a rim for engagement with said crystal and a flange offstanding substantially normal therefrom, said flange cut to provide a plurality of lugs bendable into engagement with said mounting-plate to hold said mounting-plate, dial and crystal in relatively fixed relation to said rim, said lugs provided with inclined edges serving as they are bent relatively to said mounting-plate to force said mounting-plate, dial and crystal progressively toward said rim.
- 45 3. In a clock-case, a bezel-element adapted to receive in assembled relation a crystal, a dial and a movement-mounting plate, said bezel-e-

ment having a rim for engagement with said crystal and a flange offstanding substantially normal therefrom, said flange cut to provide a plurality of lugs bendable substantially radially inward with respect to said flange and into engagement with said mounting-plate to hold said mounting-plate, dial and crystal in relatively fixed relation to said rim and a clock-movement-enclosing member for telescopic engagement with said flange.

4. In a bezel-assembly or the like, the combination with a ring-element; of a member for assembly with the said ring-element; the said ring-element including a rim and a flange offstanding therefrom in a direction substantially parallel with the axis thereof and sleeving-over the said member, the said flange being provided with a lug bent laterally into edge-engagement with the said member to hold the same between it and the said rim.

5. In a bezel-assembly or the like, the combination with a ring-element; of a member for assembly with the said ring-element; the said ring-element including a rim and a flange offstanding therefrom in a direction substantially parallel with the axis thereof and sleeving-over the said member, the said flange being provided with a lug having an inclined edge-face and bent laterally into engagement with the said member, the said inclined edge-face functioning to force said member toward said rim with progressively-increasing firmness as said lug is bent relatively to said flange.

6. In a bezel-assembly or the like, the combination with a ring-element; of a plurality of members for assembly with the said ring-element; the said ring-element including a rim and a flange offstanding therefrom in a direction substantially parallel with the axis thereof and sleeving-over the said members, said flange being provided with a plurality of annularly-spaced lugs having inclined edges and bendable laterally inwardly into engagement with the particular member of said plurality of members which is located adjacent said lugs, the said inclined edges serving to progressively force the said plurality of members into intimate contact and to hold them firmly against said rim as said lugs are bent relatively inward with respect to the said flange.
